SPINNING MECHANISM

Herbert Reinicke, Ebingen, Germany

Application November 29, 1950, Serial No. 198,055
In Germany, November 30, 1949

13 Claims. (Cl. 57—51)

1

The invention relates to improvements in spinning mechanism.

In spinning machines it has been the practice to twist the fibrous material with a view to strengthening the sliver or roving and to draft it at the same time. In the conventional systems of this kind such as crossed rollers or aprons, hyperboloid cylinders or twisting head cylinders there is a fixed relationship between the twisting process and the delivery. In view of the various characteristics of the different kinds of fibres, such as animal, vegetable, natural, and artificial, in respect to their length, surface quality and the number of fibres in a given section of thread, it is, however, necessary to adapt the twisting process to the respective delivery or height of draft, in other words, to change the permanent relation between twisting and delivery into a variable one. Besides, it is desirable, particularly for short stapled fibrous material, such as is processed in the spinning of carding wool, to twist the fibrous material so as to prevent any so-called false-twist, i. e., two opposite twists in the drafting field, from being given into the sliver or roving as is produced when using conventional means for twisting such as twisting tubes.

One of the objects of the present invention is to provide some means enabling the relation between twisting and delivery to be varied and a proper twist to be obtained.

The invention consists in that the twist producing delivery and drafting element, respectively, is provided with an individual drive each for twisting and drafting, each of said drives being variable, preferably infinitely.

Another object of the invention is to enable the strengthening and equalisation of the sliver or roving on leaving the delivery element to be maintained also in the spun yarn, in other words, to avoid a so-called false-twist. Accordingly, it is proposed to arrange the twist producing delivery and drafting element, respectively, in such a manner that the twist of the finished yarn is passed into the twist producing delivery and drafting element, respectively, in the same direction of twist which has been imparted to the sliver or roving by the delivery or drafting element.

A further object of the invention is to eliminate any thickenings in the thread or yarn. To achieve this the twist producing delivery and drafting element, respectively, can, for instance, be controlled by some gearing means in such a way that the draft will be increased or decreased periodically or even stopped intermittently. The same

result can also be obtained if the drafting drive of the twist producing delivery and drafting element, respectively, is influenced correspondingly. With these and other objects in view, the invention is illustrated on the accompanying drawings:

In the drawings, in which like reference numerals indicate like parts,

Fig. 1 is a schematic side elevation of the mechanism according to the invention as arranged between the feed rollers of the drafting system and the spindle of a spinning machine;

Fig. 2 is a longitudinal section through the mechanism according to the invention;

Fig. 3 is a plan view of Fig. 2;

Figs. 4 and 5 are a front and side elevation, respectively, of the bearing body carrying the delivery and drafting rollers, respectively;

Figures 6 and 7 are front and side views, respectively, of the driven element of a Geneva drive forming a part of the drive to the drafting rollers;

Figures 8 and 9 are front and side views, respectively, of the driving element of the Geneva drive;

Fig. 10 is a longitudinal section through another modification of the invention using endless aprons for the roving or sliver.

Fig. 11 is a plan view of Fig. 10;

Fig. 12 is a schematic side elevation showing the path of the roving or sliver through the feed rollers of the drafting system in a spinning machine and through the mechanism according to Figs. 10 and 11;

Fig. 13 is a longitudinal section through another embodiment of the invention in which the drafting elements are situated below the bearing body;

Fig. 14 is a view of Fig. 13 from below;

Fig. 15 is a schematic view showing the path of the roving or sliver through the mechanism according to Figs. 13 and 14.

Fig. 1 shows the path of the roving or sliver running from the bobbin and bobbin driving drum (not shown) through the two feed rollers 2;

3. The roving or sliver then reaches the two drafting rollers 4, 5 and thence, as usual, the spindle and cop, respectively, as indicated by the arrows shown. The drafting rollers 4, 5 do not only revolve in the direction of feeding, but they also rotate at the same time around the axis of the sliver or roving 1, gripping and twisting same during said rotation.

The mode of operation of the device by which these movements of the rollers 4, 5 are obtained is shown in Figs. 2 to 9.

The bearing body 6 supporting the two drafting rollers 4, 5 and rotating around the axis of the roving or sliver is illustrated in Figs. 2, 4 and 5. Ball bearings 9 and 10 are mounted on the cylindrical ring surfaces 7, 8 of the bearing body 6. The inner bearing race 11 of the ball bearing 9 is secured to the bearing body 6. The outer race 12 is fixed to a support 13 which is secured by screws 33 to the supporting arm 15 forming part of the frame. Thus the bearing body 6 is rotatably mounted in the supporting arm 13 by means of the ball bearing 9. Drive to the bearing body 6 is from the pulley 16 which is secured thereto, for instance by bolting. The drive is by a belt 17 applied to the pulley 16.

The inner race 14 of the ball bearing 10 is secured to the bearing body 6. The outer race 18 is secured to the inner wall of the pulley 19, which either forms a unit with the bevel gear 20 or both parts are individual ones which are connected to each other by some known means. By a belt 21 the pulley 19 and thereby the bevel gear 20 can be rotated in relation to the bearing body 6 because of the provision of the ball bearing 10.

The bands or belts 17 and 21 are individually driven, for instance by an infinitely variable gearing which is schematically shown in Fig. 1 by the discs 75 and 76.

The bearing body 6 has a bore 22 extending throughout the full length of the body and serving as a passage for the roving or sliver 1. The bearing body is further provided with two fork-like lugs, 23, 24 carrying the supporting pins 25, 26 on their outer surfaces. Axially aligned bores 27, 28 are provided in the inclined lugs 23, 24. The axle 29 of the drawing roller 5 fits these bores. As is to be seen more particularly from Fig. 3, the drafting roller 5 is supported between the inclined lugs 23, 24 and secured to the axle 29.

The other drafting roller 4 yieldably contacts the drafting roller 5 (Figs. 2, 3) with the aid of spring 37. The roller 4 rotates freely on the nub 34 of a crank lever 35 provided therefor, said lever having an eye 36 for mounting on the pin 26 on which it is permitted to rotate but not to move axially.

One end 38 of the spring 37 is secured to lug 24. The spring is guided under tension in such a way that by its opposite end 77 the crank lever 35 or the drafting roller 4 is resiliently pressed against the drafting roller 5 (Figs. 2, 3, 5). Drive to the two drafting rollers 4, 5 is ensured through bevel gear 20 which, in turn, is driven by the pulley 19 through belt 21. The bevel gear 20 meshes with the small bevel gear 39 thus causing the drafting rollers 4, 5 to be driven directly.

Twist is given to the sliver or roving by the drive 16, 17 to the bearing body 6 in the manner described, while drafting of the sliver or roving is effected at the same time by the rollers 4, 5 operated by the drive 19, 21. As the speed of driving elements 16, 17 and 19, 21, respectively, may be regulated, the drafting can be brought into the desired relation to the twisting.

If drafting i. e., the rotation of rollers 4, 5, is to be achieved intermittently, or stopped for a short time, this can be obtained by varying the drive through 19, 21 correspondingly by varying the number of revolutions of the drive 19, 21 in relation to that of the drive 16, 17 in such a manner that the yarn is twisted but not drafted.

Periodical drafting can, however, also be performed by a special control gear as shown in Figs. 2 to 9.

For this purpose, the axle 29 of the drafting

roller 5 carries a Geneva wheel 30 having the usual driving grooves 31 and notches 32.

The Geneva wheel is engaged by pins 43, 44 of the driving disk 41, on the hub 40 of which is supported the driving bevel gear 39 meshing with the bevel gear 20.

If the bearing body 6 is held stationary and the bevel gear 20 driven, the small bevel gear 39 rolls on the bevel gear 20, thereby driving the driving disk 41. Thus, the pins 43, 44 engage the grooves 31 of the Geneva wheel 30. The full segments 45, 46 on the disk 41 co-operate in the usual manner with the segmental recesses 32 provided on the Geneva wheel 30. Thus an intermittent rotation is obtained according to the design of the Geneva wheel 30 and is transmitted to the two drafting rollers 4, 5.

The above description is only meant to illustrate the intermittent movement obtained by the rolling motion of the bevel gear 39. In practical use, the bearing body 6 is not held stationary, but is caused to rotate by means of the belt 17, whereas the bevel gear 20 is either held stationary or rotated by the belt 21 at a different speed and, as the case may be, in a different direction of rotation than the bearing body 6. Here again, a rolling motion of the bevel gear 39 is accomplished and thereby an intermittent rotation of the two drafting rollers 4, 5 obtained, said rollers permitting intermittent drafting of the roving or sliver.

Whereas a separate pair of drafting rollers 4, 5 is coordinated to each thread of roving or sliver, the feed rollers 2, 3 extend over the full length of the machine or part of it. They may rotate at constant speed, but they can also be driven intermittently in the same manner as the drafting rollers 4, 5 by suitable means, such as a Geneva mechanism. Despite the temporary stoppage of the drafting rollers, the speed of rotation of same is so selected in relation to the speed of the feed rollers 2, 3 that adequate drafting is ensured.

The rotational movement of the thread of sliver or roving is effected by the rotation of the bearing body 6. Rotating around its central longitudinal axis, said body drives both the Geneva gears 30, 41 supported therein and the drafting rollers 4, 5, thus causing a rotation around the thread of sliver or roving. Since the latter is gripped between the rollers 4, 5, it is twisted during said rotation. The speed of rotation of the bearing body 6 can be varied within wide limits. For this purpose, the drive of the belt 17 is derived from an infinitely variable gearing as shown schematically at 75.

In like manner, the drive of the belt 21 can be obtained from an infinitely variable gearing 76, it being also possible for the pulley 19 to be at rest or to rotate in reversed direction of rotation. Thus the rolling speed of the bevel gear 39 and consequently the drafting speed of the rollers 4, 5 can be varied within wide limits just as the degree of twist of the thread of sliver or roving 1. In the arrangement according to this invention, the drafting and twisting forces will become effective at the same point of the roving sliver. Due to the fact that the rollers 4, 5 resiliently contact each other, a satisfactory conveying, or feeding, of the sliver or roving, even of varying thickness, is ensured.

Figs. 10 to 12 show the path of the sliver or roving through a mechanism with endless conveyor aprons. In these views, parts corresponding to those of Figures 1-9 bear the same numerals with a subscript "a." Starting from the bobbin and bobbin driving drum (not shown), the thread passes between the two feed rollers 2a, 3a. The

feed roller 2a can be rotated intermittently by an intermittently operating gear, for example as Geneva gear mechanism. The roving or sliver is thereby fed with variable speed to the two conveyor aprons 51, 52, temporary stopping of the feed being also possible.

The conveyor aprons 51, 52 embrace the rollers 4a and 5a, respectively, with guiding rollers 53, 54 which rotate together with the bearing body 6a being provided to ensure a large area of contact between the aprons and rollers 4a, 5a. These guide rollers also ensure a narrow spacing of the return sides of the conveyor aprons, thereby permitting the latter to be arranged in the relatively narrow passage 22a of the bearing body 6a.

Fitted to the bottom end of the bearing body 6a and rotating with same are two rollers 55, 56 which are arranged to rotate in a flange-like bearing body 56a. The latter has bores to fit the ends of pins 57, 58. The nuts 59, 60 are seated on the threaded bolts 61, 62 which can be screwed into the threaded bores of the whirl 16 as may be desired, thus providing for some adjustment of the tension of the conveyor aprons 51, 52. Owing to the pull of the conveyor aprons 51, 52, the flange-like bearing body 56a is drawn against the adjusting nuts 59, 60.

As in the embodiment shown in Figs. 1 to 3, the whole device is carried by the support 13a having a ball bearing 63 for taking up vertical thrust and permitting the rotation of the bearing body 6a. The latter is substantially designed as described with reference to Figs. 1 to 3. The rotation of said body in relation to the support 13a is additionally ensured by needle bearings 64. Needle bearings 65 are also provided to facilitate rotation of the pulley 19a. Again, the rollers 4a and 5a are needle bearing mounted, as is to be seen more particularly from Fig. 11.

To ensure a quick stopping of the rotating pulleys 16a, 19a, a brake of conventional design is provided within the reach of the lug 66 for braking the stepped parts 67, 68 of the pulleys 16a, 19a.

Referring to Figs. 13 to 15, a still further modification is shown and wherein parts corresponding to those of Figures 1-9 bear the same numerals with a subscript "b" added. In Figures 13-15, the sliver or roving thread passes an arrangement in which the rollers for drafting and twisting are located at the bottom end of the bearing body 6b. The bearing body 6b is similar in design as shown in Figs. 1 to 3, except that the lugs for mounting the drafting and twisting rollers 4b, 5b project downwards. Besides, said lugs are extended in length, carrying another roller 69. The sliver or roving thread passes between the rollers 4b, 5b, 69 and in doing so is resiliently pressed against the rollers 5b and 69 by the spring loaded roller 4b mounted in the crank lever 35b, which arrangement ensures an easy passage of thread thickenings between the rollers owing to the fact that the roller 4b is arranged to yield. By so pressing the thread at two points, proper guidance is secured and slipping of same is avoided.

The roller 4b is driven by the bevel gear 39b meshing with the bevel gear 20b in the same manner as described with reference to Figs. 1 to 3. The spur gear 70 rotates together with the bevel gear 39b, both being mounted on a common pin 25b. Spur gear 70 drives another spur gear 71 which together with roller 4b is carried by the hub of the crank lever 35b, thereby effecting the rotation of the roller 4b. In the embodiment according to Fig. 10, showing endless conveyor

aprons 51, 52, the roller 4a is driven in the same manner.

In contrast to the arrangement shown in Figs. 1 to 3, the intermittent feed of the sliver or roving thread in the modifications according to Figs. 10 to 15 can be effected by the feed rollers 2a, 3a or 2b, 3b. This is achieved by including in the drive a Geneva drive mechanism for driving one of each set of the feed rollers intermittently as diagrammatically illustrated in Figures 13 and 15. Owing to the fact that the travelling speed is constantly changed and, as the case may be, the driven feed roller is stopped temporarily, on the one hand, and the conveyor aprons 51, 52 or the rollers 4b, 5b, 69, are driven continuously, on the other hand, longitudinal vibrations are imparted to the sliver or roving thread facilitating the drafting of the thick places in the latter.

When using conveyor aprons, any winding of the thread around the rollers 4a, 5a is absolutely impossible. The thread is rather gripped by the conveyor aprons 51, 52 and automatically fed out at the opposite end of the aprons. The arrangement shown in Fig. 13 gives easy access to those points at which winding of the thread around the rollers could occur. Accordingly, with an arrangement so designed, the introduction of the thread is facilitated or a strayed thread can be easily brought into correct position.

The modification according to Fig. 13, too, has ball and needle bearings to facilitate the rotation of the bearing body 6, pulley 19b, and the rollers 4b, 5b, 69.

In the arrangements according to Figs. 10 to 15, speed control for drafting and twisting is practicable in the same manner as in the modifications referred to above, viz. by influencing the variable speed gearings corresponding to the ones shown in Figure 1, and which in Figure 12 are shown at 75a and 76a, and in Figure 15 at 75b and 76b.

I claim:

1. In a mechanism for the simultaneous twisting and drafting of fibrous materials; a body having a bore therethrough, means supporting said body for rotation on the axis of said bore, drafting means carried by said body for rotation therewith and adapted for being driven to draw fibres on the axis of the said bore, independent drive means for said body and draft means; and means in the drive means for said draft means providing for cyclic variation of the speed of said draft means for imparting a longitudinal vibration to the fibres being drafted to produce a uniform product.

2. In a mechanism for the simultaneous twisting and drafting of fibrous material; a body having a bore therethrough and mounted for rotation on the axis of the said bore, draft means mounted on said body on axes transverse to the axis of said bore and drivable for drafting fibres in the direction of the axis of said bore, independent drives for said body and said draft means adapted for variable speed operation to provide for the proper twisting and drafting of the fibres, and the drive means for said draft means including intermittent driving means, whereby said draft means operates at a cyclically variable speed, thereby to impart a longitudinal vibration to the fibrous material being operated.

3. In a mechanism for simultaneous twisting and drafting of fibrous material; a body having a bore therethrough and mounted for rotation on the axis of said bore, draft rollers mounted on one end of said body on axes transverse to the

75 one end of said body on axes transverse to the

axis of said bore, said rollers being rotatable on their own axes and also rotatable with said body, means for driving said body in rotation, means for driving said rollers in rotation on their own axes independently of the driving of said body, and the said means for driving said rollers including a Geneva drive, whereby the rollers are alternately stopped and driven.

4. In a mechanism for simultaneous twisting and drafting of fibrous material; a body having a bore therethrough and mounted for rotation on the axis of said bore, a pair of draft rollers mounted on one end of the body on axes transverse to the axis of said bore so as to rotate with the body while also being rotatable on their own axes, a Geneva wheel connected with one of said rollers, a Geneva drive element operatively associated with said Geneva wheel, and means for independently driving said body and said driving element.

5. In a mechanism for simultaneous twisting and drafting of fibrous material; a body having a bore therethrough and mounted for rotation on the axis of said bore, a pair of draft rollers mounted on one end of the body on axes transverse to the axis of said bore so as to rotate with the body while also being rotatable on their own axes, a Geneva wheel connected with one of said rollers, a Geneva drive element operatively associated with said Geneva wheel, and mounted on said body, a bevel gear rotatably mounted on said body, another bevel gear connected with said drive element and meshing with the bevel gear on said body, and means for independently driving said bevel gear on said body and the said body.

6. In a mechanism for simultaneous twisting and drafting of fibrous material; a body having a bore and mounted for rotation on the axis of the said bore, a draft roller mounted on one end of the body on an axis transverse to the axis of said bore so as to be rotatable with the body and also rotatable on its own axis, a second drafting roller carried by the body and resiliently urged against the said first roller, a Geneva wheel connected with said first roller and having a plurality of drive grooves therein, a drive disk on the said body having a plurality of drive elements engageable with said grooves, a first bevel gear rotatably mounted on said body and a second bevel gear meshing therewith and connected with said drive disk, and means for independently driving said first bevel gear and said body.

7. In a mechanism for simultaneous twisting and drafting of fibrous material; a body having a bore and mounted for rotation on the axis of the said bore, a draft roller mounted on one end of the body on an axis transverse to the axis of said bore so as to be rotatable with the body and also rotatable on its own axis, a second drafting roller carried by the body and resiliently urged against the said first roller, a Geneva wheel connected with said first roller and having a plurality of drive grooves therein, a drive disk on the said body having a plurality of drive elements engageable with said grooves, a first bevel gear rotatably mounted on said body and a second bevel gear meshing therewith and connected with said drive disk, a first pulley connected to said first bevel gear and a second pulley connected to said body, and separate drive belts engaging said pulleys for driving said body and draft rollers independently.

8. In a mechanism for simultaneous twisting and drafting of fibrous material; a body having

a bore and mounted for rotation on the axis of the said bore, a draft roller mounted on one end of the body on an axis transverse to the axis of said bore so as to be rotatable with the body and also rotatable on its own axis, a second drafting roller carried by the body and resiliently urged against the said first roller, a Geneva wheel connected with said first roller and having a plurality of drive grooves therein, a drive disk on the said body having a plurality of drive elements engageable with said grooves, a first bevel gear rotatably mounted on said body and a second bevel gear meshing therewith and connected with said drive disk, a first pulley connected to said first bevel gear and a second pulley connected to said body, and separate drive belts engaging said pulleys for driving said body and draft rollers independently, said belts being adapted for being independently driven by variable speed driving means.

9. A method for simultaneously twisting or drafting a slab or roving comprising: delivering the said slab or roving through feed rollers, receiving the said slab or roving between cooperating draft elements, rotating the said draft elements in a plane transverse to the length of said slab or roving for imparting a twist to the same, and periodically increasing and decreasing the speed of operation of said drafting means.

10. In a method for simultaneously twisting and drafting fibrous material; engaging the material at spaced points, relatively rotating the material at the said spaced points for imparting a twist to the material, moving the material at one of the said points in the direction of its length at one speed and in the same direction at another speed at the other point, and periodically and continuously varying the said speed at one of said points.

11. In a method for simultaneously twisting and drafting fibrous material; delivering the material in the direction of its length at a fixed speed at one point, engaging the material at a second point spaced from said one point and continuously twisting the material at the said second point, and intermittently driving and stopping the material at said second point to impart a longitudinal vibration to the material being drafted.

12. In a method for simultaneously twisting and drafting fibrous material; delivering the material in the direction of its length at a fixed speed at one point, engaging the material at a second point spaced from said one point and continuously twisting the material at the said second point, and intermittently driving and stopping the material at said second point to impart a longitudinal vibration to the material being drafted, the average speed of movement of the material at the second point being greater than the speed of movement thereof at the said first point, whereby the material is drafted during its travel between said points.

13. In a method for simultaneously twisting and drafting fibrous material; delivering the material in the direction of its length at a fixed speed at one point, engaging the material at a second point spaced from said one point and continuously twisting the material at the said second point, and intermittently driving and stopping the material at said second point to impart a longitudinal vibration to the material being drafted, the average speed of movement of the material at the second point being greater than the speed of movement thereof at the said first

point, whereby the material is drafted during its travel between said points, and there being a plurality of the said drivings and stoppings of the material at said second point during the length of time required for a predetermined portion of 5 the material to travel between said points.
